UNITED STATES PATENT OFFICE.

REUBEN B. BENJAMIN, OF CHICAGO, ILLINOIS.

SAFETY DEVICE FOR MACHINERY.

1,046,373.

Specification of Letters Patent. Patented Dec. 3, 1912.

Application filed October 28, 1911. Serial No. 657,330.

To all whom it may concern:

Be it known that I, REUBEN B. BENJAMIN, a citizen of the United States, residing at Chicago, in the county of Cook and State of Illinois, have invented new and useful Improvements in Safety Devices for Machinery, of which the following is a full, clear, concise, and exact description, reference being had to the accompanying drawing, forming a part of this specification.

My invention relates to protective devices for stamping presses, die presses and the like. It is, in fact, applicable to any form of press or machine which is adapted to be intermittently thrown into or out of operation.

One of the objects of my invention is to provide an improvement in safety or protective attachments of that class which require the use of both hands of the operator to effect the tripping of a stamping press or the like. Heretofore in safety attachments of this character, particularly those applicable to that class of punch presses adapted to run "open," it has been possible for the operator to quickly move the controlling handles, levers or buttons, or the like, to initially start the tripping operation, and then remove one hand from the controlling or interlocking lever, button or handle, and feed the die press with that hand. That is, the safety devices have been so constructed that after they have once been set in motion they will not return to normal position upon the release of the interlocking or controlling member, but will continue to be in a position to permit the operation of the tripping mechanism. Such a device, instead of affording the maximum protection to the operator by insuring the use of both hands for tripping the machinery, tends to be a source of greater danger in that the operator, being able to set the device in motion and then return to the feeding of the press, is tempted to hurriedly set the safety devices and then, without due caution, attempt to insert the material in the machine to be operated upon, such hurry and lack of caution tending rather to increase the danger than otherwise.

It is one of the objects of my invention to provide an electrically controlled device which necessitates the use of both hands of the operator until the machinery is actually tripped. I have found that after the machinery has actually tripped, the period be-

tween the actual tripping thereof and the descending of the die, in event it is a stamping press, is so short that it would be practically impossible for an operator to get his 60 hands in a dangerous position.

It is a further object of my invention to provide a device which will be very sensitive in its operation and which immediately upon the removal of either hand after the 65 tripping mechanism has been set in motion, will permit the tripping mechanism to return to normal position.

For the purpose of disclosing my invention I have illustrated one embodiment 70 thereof applied as a safety attachment to a punch press having a reciprocating plunger.

In the drawings illustrating the embodiment of my invention and the application thereof—Figure 1 is a side elevation of a 75 plunger press showing my safety attachment applied thereto; Fig. 2 is a front elevation of the punch press with my attachment applied thereto; Fig. 3 is a detail sectional view showing the tripping mechanism of the punch press; Fig. 4 is an enlarged detail elevation of the connecting mechanism between the tripping lever and the tripping mechanism of the punch press; Fig. 5 is an end elevational detail view of 80 85 the controlling magnet and the manner of attachment thereof; Fig. 6 is a plan view of the tripping lever connection; Fig. 7 is a side elevation showing the tripping lever connection in non-operative position; and Fig. 8 is a diagrammatic view of the circuit 90 connections.

Referring now to the press illustrated in the drawings, this machine takes the form of a stamping press of ordinary construction. This press has the usual framework carrying a table 2 over which operates the usual reciprocating punch-carrying member 3. An eccentric crank on the driving shaft 4 serves to reciprocate the punch-carrying 95 member for the purpose of pressing out the material. The shaft 4 is driven from a pulley wheel 5 which is loosely mounted on the shaft and adapted to run free thereon except during the intervals it is connected to 100 the shaft by the clutching mechanism. The clutching mechanism may be of any desired construction and is illustrated as consisting of a rotatable key 6 mounted in a suitable slot in the shaft 4 and adapted when rotated to engage in slots or openings 7 105 formed in the hub of the pulley 5. Inter-

posed between an abutting stop 8 carried on the collar of the shaft and the lower end of the arm 9, integrally formed with the key, is a coiled spring 10 which has a tendency to move the arm to a position to give the key 6 a half turn to throw the clutch into a connecting position. When the pulley is running free or when the press is in an untripped position the arm 9 is held against movement, under the influence of the spring 10, by a tripping stop 11 pivoted at 12 to the frame of the machine. This tripping stop is moved out of the path of the arm 9 to permit the clutch to trip by the movement of a tripping rod 14.

The lower end of the rod 14 is connected by a link mechanism with the operating lever 15, this link mechanism being so constructed that it is normally inoperative to transmit the movement imparted by the operating lever 15 and is only rendered operative by the use of the second hand of the operator. The operating lever 15 is pivoted to a stud or bolt 16 extending from the frame of the machine and the connecting mechanism between this lever and the rod 14 comprises a pair of links. One of the links, 17, is pivotally connected to the lever 15 at 18 and has its opposite end free; the other link, 19, is provided with a slot 20 which fits over a pin 21 passing through an eye 22 formed in the lower end of the rod 14 and is pivotally connected at 23 with the free end of the link 17. A coiled spring 24, having one end engaging the lever 15, is wrapped around the pivot point 18 of the link 17 and has its other end engaging the lower portion of a right angle flange 25 on the link 17 to hold the link in the position illustrated in Fig. 4. The eye 22 of the rod 14 fits between the bifurcated ends of a pivoted arm 26 and the pin 21 secured in the eye also extends through openings formed in the bifurcated ends of the arm 26. The opposite end of the arm 26 is pivoted on the bolt 16. The arm thus serves as a guide for the lower end of the rod 14. The centers of the pivots 18, 23 and 21 are such that when the lever 15 is depressed the two links 17 and 19 will tend to separate, as shown in Fig. 7, so that unless some means is provided for holding the links together, when the lever 15 is depressed no movement will be transmitted to the rod 14. The rod 14 is held in its raised position or in the non-tripping position and is moved to non-tripping position when disconnected from the lever 17, by the spring retracted rod 13 mounted on the side of the frame 1 and connected at its lower end to the pin 21.

In order to connect the two links together I provide a spool magnet 27 which is secured by means of a flange 28 formed thereon and suitable screws to the angular flange 25 of the link 17. It will be noted, as illus-

trated in Fig. 4, that when the parts are in normal position the lower end of the link 19 is in actual contact with the end of the spool magnet 27, and this link is preferably formed of soft iron, so that it constitutes the armature of the magnet. Therefore when the circuit through the magnet is closed the link 19 is held against separating from the link 17 and when the lever 15 is depressed motion will be imparted to the rod 14. Due to the fact that the link 19 in normal position lies in actual engagement with the core of the spool magnet, there is no air gap to be overcome by the magnet when its coils are energized to attract the link thereto, and the magnet may accordingly be made materially smaller.

The lever 15 is held in normal position by a coiled spring 28, one end of which is connected to the lever about midway of its ends and the other end of which is connected to a brace or support 29 which constitutes a continuation of the angularly extending arm 30 secured at its lower end to one of the compression bolts or tie rods 31 of the frame. In order to hold the support 29 in substantially vertical or upright position, a second bracing member 32 is secured at one end to the arm 30 and at the other end to the front tie rod 33.

The circuit through the coil of the magnet 27 is controlled by a circuit controller in the form of a push button 35 mounted on an arm 36 secured on the opposite side of the frame in substantially the same manner as is the support 29. The circuit connections of the coils of the magnet are more fully illustrated in Fig. 8. In this figure it will be noted that one terminal of the coils of the magnet is connected by a conductor 37 with one terminal of the push-button 35. The opposite terminal of the push-button is connected by the conductor 38 with one terminal of electric battery 39. The opposite terminal of the battery is connected by conductor 40 with the opposite terminal of the coils of the magnet. In place of an electric battery I may connect the conductors 40 and 38 directly with the electric lighting supply by means of a suitable plug 41, illustrated in dotted lines in Fig. 8. It will be noted that the push-button 35 is so positioned that the operator cannot depress the operating lever 15 and at the same time operate the push button 35 by the same hand.

In tripping a press the operator with one hand first closes the circuit through the magnet 27 by operating the push button 35; keeping the circuit through the magnet 27 closed with one hand, with the other hand he depresses the lever 15, and, due to the fact that the link 19 is held by the magnet 27 and the two links 19 and 17 cannot therefore separate, the movement imparted to the lever 15 will be transmitted to the rod 14.

and the tripping mechanism operated. If at any time before the press is actually tripped the operator removes either hand, the tripping mechanism will fly back to normal position. If he removes his hand from the 5 push-button 35 the circuit through the coils of the magnet 27 will immediately be opened and the links 17 and 19 permitted to separate, thereby disconnecting the operating lever 15 from the rod 14 and permitting the 10 tripping mechanism to fly back to normal position. If he removes his hand from the operating lever 15 the lever will fly back to normal position under the influence of the spring 28, and with it the tripping mechanism. It is therefore seen that until the 15 press is actually tripped both hands of the operator must be used.

While I have shown and described one 20 embodiment of my invention, it will be understood that various modifications or changes may be made therein without departing from the spirit of my invention as set forth in the appended claims.

Having thus described my invention, what 25 I claim as new and desire to secure by Letters Patent is:

1. The combination with a tripping mechanism, of a movable member for actuating 30 said mechanism, normally inoperative means for effecting an actuating connection between said movable member and said tripping mechanism, electromagnetic means for rendering said connection effecting means operative, and a circuit controller for said 35 electromagnetic means, said circuit controller being placed apart from said movable member, for the purposes set forth.

2. The combination with a tripping mechanism, of an operating member therefor, 40 connecting means for connecting the member and tripping mechanism including an electromagnetic, said connecting means being normally in operative position but inoperative to connect the lever and mechanism 45 unless the circuit through the magnet is closed, and a circuit controller for said magnet, said circuit controller and said operating member being placed apart, for the purposes set forth.

3. The combination with a tripping mechanism, of a member for operating the same, connecting means between said member and tripping mechanism including an electromagnetic 55 said connecting means being arranged to become inoperative upon the opening of the circuit through the magnet, and a circuit controller for said magnet, said controller and said member being placed apart, for the purposes set forth.

4. The combination with a tripping mechanism, of a member for operating the same, 60 electromagnetically controlled means for connecting the member and tripping mechanism, a circuit controller for controlling

the circuit through said magnet, said controller being placed apart from said member, and means for returning the tripping mechanism to non-tripping position in event either the lever or the circuit controller is 70 released before the tripping mechanism operates, for the purposes set forth.

5. The combination with a tripping mechanism, of a member for operating the same, means tending to return said member to 75 normal position, electromagnetically controlled connecting means between the lever, and tripping mechanism arranged to disconnect the lever and tripping mechanism in event the circuit through such electromagnetic means is opened, and means, positioned apart from said member, for controlling said electromagnetic connecting means, for the purposes set forth.

6. The combination with a tripping mechanism, of a member for operating the same, 80 a pair of connecting links pivoted together at one end, one of said links being connected to said member and the other of said links being connected to the tripping mechanism, 85 and said links being arranged so as to tend to separate when the lever is depressed, and an electromagnet for preventing the separation of said links.

7. The combination with a tripping mechanism, of a member for operating the same, 90 a link pivotally connected to said member and having its opposite end freely movable, a second link pivoted to the free end of said link and connected at its opposite end to 100 the tripping mechanism, electromagnetic means for fixing the free end of the link relatively to the tripping mechanism, and a circuit controller for said means, said controller being placed apart from said member, for the purposes set forth.

8. The combination with a tripping mechanism, of a member for operating the same, 105 a pair of connecting links pivoted together at one end, one of said links being connected to the tripping mechanism and the other of said links being connected to said member, said links having a tendency to separate when the lever is depressed, an electromagnet mounted on one of said links and having 110 its core arranged when the links are in normal position to engage the other link whereby when the circuit through the coils of the magnet is closed the links will be prevented from separating, and a circuit 120 controller for said magnet, said circuit controller being placed apart from said member, for the purposes set forth.

9. The combination with a tripping mechanism, of an operating member therefor, 125 connecting means between said member and said tripping mechanism, said connecting means being normally inoperative but in operative position, an electromagnet adapted, when energized, to render said connecting 130

means operative, and a circuit controller for said electromagnet, placed apart from said operating member, for the purposes set forth.

- 5 10. The combination with a trip mechanism, of a member for operating the same and normally inoperatively connected to the trip mechanism, electromagnetic means for connecting the said member and trip mechanism in operative relation, and a circuit controller for said electromagnetic means,

said controller being placed apart from said operating member, for the purposes set forth.

In witness whereof, I have hereunto sub- 15 scribed my name in the presence of two witnesses.

REUBEN B. BENJAMIN.
